ILLUMINATING DRY SHAVER

Godfrey Dalkowitz, Brooklyn, N. Y., assignor to
 American Safety Razor Corporation, Brooklyn,
 N. Y., a corporation of Virginia

Application June 21, 1938, Serial No. 214,869

1 Claim. (Cl. 240—2)

This invention relates in general to dry shavers and in particular to illuminating dry shavers, in which an arrangement for illuminating the area to be shaved is carried by the shaver and in effect forms a part thereof.

Coordinately therewith it relates to a light source peculiarly adapted to cooperate effectively with a dry shaver to secure efficient illumination of the area to be shaved.

The general object of my invention is the provision in a dry shaver of an illuminating arrangement that is simple, compact and low in cost and effective in operation and which will not necessitate any substantial change in the dimensions or contours of a dry shaver of conventional type.

The user of a dry shaver provided with illuminating means, on attempting to shave, is apt to find on looking into the mirror that the illuminating means is so positioned in relation to the shaver that it wholly or partly obstructs his view of the area to be shaved. He may further find that the illumination is insufficient or that it is improperly distributed.

He may also find that the illuminating means is readily damaged and that in order to avoid such damage extreme care in handling the shaver is required. He may even find that such damage is apt to occur during ordinary use of the dry shaver.

He may further find that if repairs are necessary or if replacement is needed, as when an incandescent bulb burns out, that the operation of removing the bulb and replacing it, or of gaining access to the parts to be repaired is extremely troublesome and time consuming.

Among the objects of my invention are therefore the provision in a dry shaver of an illuminating arrangement so positioned that it will not obscure the shaver's view in the mirror of the area to be shaved; the provision in a dry shaver of an illuminating arrangement that will throw light on an area adjacent to and a little in advance of the shaver head; the provision in a dry shaver of a lighting arrangement that permits of ready accessibility to the parts thereof; the provision in a dry shaver of an illuminating arrangement the parts of which are protected against damage during ordinary use, and the provision in a dry shaver of a lighting arrangement by which emission of light is prevented in all directions except in a direction toward the shaver head.

Among the objects of my invention is further the provision of a light source adapted particu-

larly for the production of elongated areas of illumination; the provision of a light source that is readily accommodated in a confined space; and the provision of a light source that is readily insertible into or removable from its mounting.

These objects and such other objects as will hereinafter appear or be pointed out are attained in the illustrative embodiments of my invention disclosed in the drawing wherein:

10 Figure 1 is a fragmentary sectional view substantially on the line 1—1 of Figure 2, through the shaver head carrying end portion of a dry shaver having my invention applied thereto;

15 Figure 2 is a fragmentary top plan view of the portion of a dry shaver shown in Figure 1, with the cover, shown in Figure 1 as positioned over the incandescent bulb, omitted;

20 Figures 3 and 4 are views respectively similar to Figures 1 and 2, showing a second embodiment of my invention; and

25 Figures 5 and 6 are views respectively similar to Figures 1 and 2, showing a further embodiment of my invention.

In the embodiment of Figures 1 and 2 I have shown at 10 a portion of the casing of a dry shaver of conventional type carrying a shaver head 12 and also provided with suitable mechanism such as a lever 14 pivoted at 16 to operate the shaver head. This lever may be actuated in the customary manner by an electric motor located in the casing 10. A recess 18 is shown as extending transversely across the casing, and portions of the casing 10 between this recess and the shaver head are cut away as indicated at 20 so as to form a channel or groove, for a purpose to be explained hereinafter. This channel is preferably made with its side walls 22 diverging toward the shaver head. A cover 24 for the recess 18, which may be contoured to merge with the general outline of the casing, is shown as positioned over the recess 18, so that the only outlet from the recess is by way of the channel 20.

Positioned on one side of each end of the recess 18 is shown a resilient electrically conducting plate 26, which is mounted in the wall of the casing 10 and is connected to an electrical terminal 28 on the interior of the casing.

Held in place within the recess by the clips 26 is shown an incandescent bulb L having a glass encasement 30 enclosing a longitudinally extending incandescent filament 32 and having a ferrule 34 at each end thereof. The ferrules 34 are of electrically conducting material and each is connected to one end of the filament 32. It will be

obvious that this construction permits ready insertion and removal of the bulb L.

The terminals 28 are adapted for connection to any suitable source of electric current, as through electrical conductors 29, and through this connection the filament 32 of the incandescent bulb may be energized.

The glass encasement 30 of the bulb L is shown as provided with a reflecting coating 36 whereby the light may be more effectively directed toward the shaver head as indicated in the drawing.

It will be observed that the cover 24, besides preventing the loss of light in a lateral direction, serves to protect the bulb L.

By referring to Figure 1 it will be observed that the light proceeding directly from the filament 32 to the surface to be shaved, which is designated by the latter A, will be bounded in a plane transverse to the shaver head by the lines 32-38 and 32-40, and this direct light is augmented by light reflected from the reflecting coating 36, so that altogether the bundle of light rays emerging through the channel 20 is bounded by the lines 32-42 and 32-44. It will be observed that the illuminated area is positioned immediately in front of the shaving head 12 and its width is only sufficient to illuminate the desired area. To secure illumination adjoining the shaver head 12, the casing 10 is cut away so as to deepen the channel 20 the required amount. Substantially all of the light emitted by the incandescent bulb is concentrated in this area and distributed thereover.

In a longitudinal plane relatively to the shaver head, the bundle of emitted rays may be roughly stated to be limited by the lines 46-48 and 50-52.

It will be observed that the incandescent bulb L is located within the normal contours of a conventional dry shaver, whereby no excrescences are formed on the shaver casing that would interfere, as the shaver looks into the mirror while shaving, with his view of the reflection therein of the area to be shaved.

In the embodiment shown in Figures 3 and 4 the casing of the dry shaver is indicated at 60 and the shaver head at 62. The latter is of a type differing from that shown in Figures 1 and 2, having an oscillating cutting member, and at 64 is indicated in dot and dash lines mechanism for causing the oscillating movement of said movable cutting member.

However, while the somewhat different disposition of parts necessitates some difference in the internal contours of the casing, the outer contours are substantially the same, and in particular, the recess for receiving the light source and the channel for directing the light thereof are contoured so as to distribute the light over a restricted area in advance of the shaver head.

The incandescent bulb shown in this embodiment is of the same type as that shown in Figures 1 and 2, and for that reason these parts have been denoted by the same reference numerals primed, and a detailed description thereof is unnecessary. This bulb, L', is located in a transversely disposed recess 66 within each end of which is positioned an electrical contacting plate 68 connected to a terminal 70 within the casing adapted for connection to a source of current. At the side of the recess opposed to each of said plates 68 is a spring clip 72 adapted to permit the insertion of the incandescent bulb into the recess and to hold it there once it is inserted.

A cover 74 may be provided and held in place

by any suitable or preferred means such as the screws 76, and this cover like the cover 24, cuts off the light that would normally be directed laterally from the bulb L', so that the light is confined to the channel 80, which is similar to the channel 20 of the first embodiment, and is formed by cutting away portions of the casing 60, so that the zone of illumination will have the desired position in relation to the shaver head and the desired spread.

A third embodiment of my invention is shown in Figures 5 and 6. The shaver casing and the incandescent bulb being substantially the same as shown in Figures 1 and 2, the same numerals, double primed, have been used to indicate them and detailed description thereof will be omitted as unnecessary. The bulb L'' in this embodiment is shown as supported by a spring clip 92 of semi-cylindrical contour that is connected by an extension passing laterally through the wall of the casing 10'', as shown in Figure 5, to a terminal 94 positioned within the casing 10''.

It will be seen on referring to Figure 6 that the clip 92 is shown as slotted, as at 96 whereby its ferrule engaging portion is rendered less stiff and therefore more readily manipulable when the bulb is to be inserted or removed.

It will be observed that no cover for the recess 18'' is shown in the drawing. It is to be understood that if desired, a cover might be used in this form as in the others. However it may be found that under certain conditions the cover may be dispensed with as regards protection, while the light emission may be sufficiently controlled by suitable distribution of the reflecting coating 36''.

It will be observed the tubular form of incandescent bulb disclosed herein is peculiarly adapted to the purposes of my invention. It does not require great depth for its accommodation within the casing of the dry shaver and its longitudinally distributed filament lends itself excellently to the formation of an elongated illumination zone.

Its mounting, by resilient clips engaging ferrules on the lamp, enables ready insertion and removal of the bulb in a very restricted space and the clips also act as shock absorbers tending to cushion the bulb and to protect it against damage. In these respects it is far superior to the ordinary screw and bayonet type base bulbs.

While the bulb has been described as of the incandescent filament type, it will be obvious that other types of illuminants may be found equally desirable or even more desirable. As an example I may mention luminous gaseous discharge tubes, such as the neon light, which are also of tubular form and in which the light radiations are distributed along the tube. Light sources of this type would add another element of ruggedness to the lighting arrangement.

While I have herein disclosed several illustrative embodiments of my invention it will be understood that the same may be embodied in many other forms without departing from the spirit thereof, as will be obvious to those skilled in the art, and that the disclosure herein is by way of illustration merely and is not to be interpreted in a limiting sense, and that I do not limit myself other than as called for by the prior art.

Having thus described my invention and illustrated its use, what I claim as new and desire to secure by Letters Patent, is:

In a dry shaver having a shaving head mounted in a casing of conventional type, that is, having

a substantially flattened ellipsoidal contour, adapted to be held in the hand, portions of said casing being cut away to form a transverse elongated recess in spaced proximity to the shaver head, said recess being adapted for the reception of a light source of elongated tubular form having a terminal ferrule at each end thereof, means in the ends of said recesses for engaging said ferrules and holding the light source in place, a channel leading from the mid-portion of said recess toward the shaver head, a cover removably

5 mounted over said recess and a portion of said channel, said cover having its outer surface flush with the general contours of said casing, and its inner surface serving to restrict the spread, in a direction outwardly of the casing, of the light beam issuing from the casing and said channel having outwardly diverging side walls whereby the beam of light from the recess is permitted to spread laterally to an extent commensurate with 10 the length of the shaver head.

GODFREY DALKOWITZ.
